DESIGN FOR A FLASHLIGHT

Herman G. Graubner, New York, N. Y., assignor,
by mesne assignments, to Union Carbide and
Carbon Corporation, a corporation of New York

Application October 18, 1935, Serial No. 59,121

Term of patent 14 years

To all whom it may concern:

Be it known that I, Herman G. Graubner, a citizen of the United States of America, residing at New York city, in the county of New York and State of New York, have invented a new, original, and ornamental Design for Flashlights, of which the following is a specification, reference being had to the accompanying drawing, forming part thereof, in which:

Fig. 1 is a side view of a flashlight embodying my new design;

Fig. 2 is an end view of the flashlight looking

in the direction indicated by the line 2—2 of Fig. 1; and

Fig. 3 is an end view of the flashlight looking in the direction indicated by the line 3—3 of Fig. 1.

I claim:

The ornamental design for a flashlight, substantially as shown and described.

In testimony whereof, I affix my signature.

HERMAN G. GRAUBNER.
